SIGNAL CONTROLLING MECHANISM AND
SYSTEM

Harrison Irving Turner and Ernest Richard Freeberg, Moline, Ill., assignors, by mesne assignments, to Eagle Signal Corporation, Newton, Mass., a corporation of Massachusetts

Application July 20, 1934, Serial No. 736,266

16 Claims. (Cl. 177—337)

This invention relates to signal controlling mechanism and system, and more particularly to systems and equipment for controlling signals employed for governing highway traffic.

5 Such signaling systems are sometimes considered as falling into one or the other of two general classes, mechanism and systems falling within one of which classes will be hereinafter designated as being of the "pretimed" or "timed cycle" 10 type and that within the other of which will be hereinafter referred to as the "traffic responsive" or "traffic actuated" type; the word "traffic" thus employed being intended to allude both to vehicular and to pedestrian traffic.

15 It is an important object of this invention to provide a signal controlling system and mechanism therefor, which is susceptible of adjustment and adaptation, readily accomplished by users of ordinary intelligence and without special 20 facilities, for the purpose of meeting the greatest practicable proportion of the diverse circumstances and conditions presented in efforts to promote safe and expeditious movements of highway traffic.

25 It is another important object to provide highway traffic signal controlling mechanism which is suited for certain combinations of pretimed cycle operation with traffic responsive service.

It is a further important object to provide 30 simple and readily applied means whereby highway traffic signal controllers of certain existing well-known and widely used types may be readily and inexpensively adapted for traffic responsive service.

35 It is a further object to provide a signal controlling system involving the use of one or more push buttons or other circuit controllers whereby normal pretiming of a sequence of light or other signal aspects for governing movement of vehicles may be changed to a sequence including 40 an added so-called "pedestrian period" during which both vehicle and pedestrian movements will be suitably governed and guided.

A further object is to provide means for effecting signal display during a so-called "pedestrian period" such as to effect clearance of the intersection and/or needed portions of highways to permit simultaneous pedestrian movements in and through several or all possible 50 channels.

Another object is to provide means whereby least disturbance will result in the movement of traffic in a channel deemed to have superior importance (as, for example, that of an arterial highway), resultant from interruption of the

normal course of a predetermined cycle of changes of signal aspects, such as may be caused by the actuation of traffic responsive contacts, by inclusion of any special period (such as a pedestrian period) only at a predetermined stage of 5 such normal cycle.

A further important object is to provide means whereby differing pretimed cycles of signal aspects may be selectively rendered effective, through actuation of traffic responsive contacts 10 or otherwise, and whereby differences between such differing cycles may reside in the number and/or the character and/or the duration of any or all of the component signal aspects.

It is a still further object to provide means 15 whereby the display of any signaling aspect occurring because of actuation of traffic responsive contacts will be preceded by a warning signal for traffic in the channel or lane for which a permissive or "go" signal immediately preceded.

Still other objects are to provide so-called "memory of actuation" of traffic responsive contacts; delay of such "memory" feature whereby actuation of traffic responsive contacts later than a predetermined stage of a given cycle will not 20 cause alteration of the characteristics of the cycle then in progress but will suitably alter the next succeeding cycle, and whereby during the course of a cycle the characteristics of which have been or are to be modified resultant from such 25 contact actuation, further contact actuation occurring before a predetermined stage of such cycle will not affect the characteristics of the next succeeding cycle; to provide for maintenance

of substantially synchronous relationship between one and another of a plurality of traffic signal controllers having the foregoing characteristics, or between such controllers and a master or a central office controller; to provide a type of traffic signal controller which will cause display 30 of a signal for directing certain traffic (as, for example, a "right turn" arrow) at all times except during some abnormal period (as, for example, a "pedestrian period"); to provide means whereby the overall length of the operating cycle of traffic 35 controllers embodying any or all of the foregoing characteristics may be increased or decreased from a master point or central office, or, whereby, in lieu of such increase or decrease, the normal signaling cycles may be correspondingly sus-

40 pended, and be replaced by desired intermittent or flashing signals; to render traffic responsive contacts ineffective for altering cycle characteristics during conditioning for such intermittent or flashing signals; to provide traffic signal con- 45

50

55

trolling mechanism whereby any or all of the foregoing revisions of operating characteristics may be accomplished without utilization of change gears or other means of such character as to present opportunities for inadvertent disarrangement of intended cycle characteristics incidental to substitution of cycles of one characteristic for those of another.

A further important object of this invention 10 is to provide improved timer and circuit controlling mechanism which, for the accomplishment of all, any one or of any group of the foregoing objects, shall be of greater effectiveness, more reliable, composed of a smaller number of 15 parts severally characterized by strength, durability and facility of assemblage, as well as amenable to a low cost of manufacture.

Other and more specific objects and advantages 20 will appear in the hereinafter following description of an illustrative embodiment of this invention, or will be apparent to those skilled in this art.

For the purpose of enabling this invention to be more readily understood, an embodiment 25 thereof is shown in the annexed drawings and hereinafter described, however, such embodiment, though practical, is by no means the only one which the invention may assume, wherefore the invention is not confined to any strict conformity 30 with the more or less diagrammatic representations of the drawings but may be changed and modified in various particulars so long as such changes and modifications make no material departures from the invention, as more particularly 35 set forth in the annexed claims.

In the accompanying drawings, like parts are 40 designated by the same reference characters throughout the several views in which

Figure 1 is a front elevation of a traffic signal 45 controller embodying this invention;

Fig. 2 is a somewhat diagrammatic isometric view of the signal mechanism shown in the right-hand portion of Fig. 1;

Fig. 3 is a schematic representation of circuit 45 connections suitable for association with the traffic signal controller of Fig. 1, together with signal lamps, traffic responsive contacts and a master controller arranged in cooperative relationship therewith;

Fig. 4 is a schematic representation of a simple manner of associating the timer mechanism 50 of Fig. 1 with a pair of signal lamps;

Fig. 5 is an enlarged view of one of the cam assemblies of Fig. 2, with certain parts broken 55 away;

Fig. 6 is a perspective view of one of the spacer 60 rings of Fig. 5;

Fig. 7 is a chart representative of the component periods which comprise a cycle of the operation 65 of the system arranged in accordance with Figs. 1, 2 and 3, without a pedestrian period;

Fig. 8 is a chart representative of a similar 70 cycle including a pedestrian period;

Fig. 9 is a chart representative of the traffic 75 movements permitted through the association of a group of traffic signal controllers with a master controller, in accordance with Fig. 3;

Fig. 10 shows another type of street intersection 80 for control of traffic to which systems in accordance with Figs. 1, 2 and 3 may be readily adapted;

Fig. 11 is a chart showing the relative characteristics of component periods of a system similar to that of Figs. 1, 2 and 3, but arranged for 85 use at an intersection such as indicated in Fig.

10, substituting a "go" period for a minor intersecting highway for the "right turn" signals and the pedestrian period of said prior figures;

Fig. 12 is a chart, similar to Fig. 9, representative of the traffic movements permitted through the association of a group of traffic signal controllers with a master controller in accordance with Fig. 3, with modified setting of the cam assembly, and

Fig. 13 is an across-the-line diagram schematically representing the circuit connections more or less pictorially illustrated in Fig. 3.

The traffic signal controller of Fig. 1 comprises a panel 14 upon which are mounted the timer mechanism CD, the signal circuit controlling 15 mechanism SC responsive thereto, the pedestrian memory relay P and the flashing service control relay N; said relays being situated below the timer mechanism CD.

The timer mechanism CD includes means for 20 establishing the relative durations of the respective periods or components of a cycle of the operation of the controller, together with facilities for manually altering the relative durations thereof; which facilities include the dial 150 and 25 the arms 149, 151, 152 and 153 associated therewith.

As shown in Fig. 3, the pins 151', 152' and 153' are secured to the free ends of the arms 151, 152 and 153, respectively. In order to adapt 30 the controller for effecting certain groupings of signaling aspects, the fourth arm 149 may be equipped with a pin corresponding to the pins 151', 152' and 153'; but, in the interests of clearness, such pin is omitted from Fig. 3.

As indicated by Fig. 1, portions of the arms 149, 151, 152 and 153 carry reference pointers or lines closely associated with indicia 150' provided upon the face of the dial 150 in order to facilitate determinations for required relative settings 40 of said arms.

As best shown by Fig. 3, the dial 150 and arms 149, 151, 152 and 153 are carried by the shaft 119; although the relative positionings of these and other parts along the length of said shaft 45 are diagrammatically expanded far beyond usual practice, in order to facilitate clear representation of the various parts.

The dial 150 is fixed upon the shaft 119, and the arms 149, 151, 152 and 153 are so secured to 50 the shaft as to be capable of rotary movement with relation thereto; said arms being frictionally driven by the rotation of said shaft with sufficient force to prevent relative displacement during normal operation of the mechanism, while 55 permitting manual setting of said arms with relation to the dial 150.

The insulating cams 131 and 132 are also fixed upon the shaft 119, as is the gear 136 which meshes with the pinion 135 driven by the motor 60 M2.

The ratio of the gearing 135, 136 between the motor M2 and the shaft 119 is such that when the motor is operating from the intended supply source circuit, the shaft 119 will make a full 65 revolution in a time selected for a complete signaling cycle, if operating independently of a master timer or controller; or, in a time not greater than and preferably somewhat less than an intended cycle if operating (as shown in Fig. 70 70) in connection with a master timer.

The contacts 63 are so associated with the cam 131 as to be closed during a comparatively small proportion of each revolution of the shaft 119 and to remain open at all other times; and the 75

contacts 64 are so associated with the cam 132 as to be thereby held closed throughout each revolution of shaft 119 except a part of that portion during which the contacts 63 are closed.

- 5 A dog 154, which is fixed upon the shaft 158, extends in the path of the free ends of the pins 151' and 152'; the radial distance of said pins from the shaft 119 being such that the pin 151' will pass above and the pin 152' will pass below 10 the dog 154. Cam surfaces are formed near the free end of the dog 154 so that as the pins 151' and 152' are carried past said dog, said dog will be moved to turn the shaft 158 in clockwise and counter-clockwise directions, respectively.
- 15 The contact arm 157 is fixed upon the shaft 158, to be rocked in one direction or the other as the pins 151' and 152' are carried past one side and the other of the dog 154; and the contacts 65 and 66 are so positioned that the free end of 20 the arm 157 will engage the contact 65 while the pin 151' is moving past the free end of the dog 154 and said contact 66 will be engaged by arm 157 during actuation of dog 154 by pin 152'. A spring 159 is so applied to the arm 157 as to tend 25 to retain same in a position intermediate the contacts 65 and 66.

The arm 155 is pivoted on the shaft 156 and extends in the path of the pin 153'; but does not extend in the paths of the pins 151' and 152' 30 which are situated at less radial distances from the shaft 119 than said pin 153'. A spring 160 is so applied as to tend to swing the arm 155 into the path of the pin 153' and the contacts 67 are so associated with the arm 155 that, during engagement of the free end of said arm by the pin 153', said contacts will be closed for a suitable interval, for a purpose which will be hereinafter more fully explained.

As indicated in Fig. 4, the timer mechanism thus far described, with but little modification, will provide for controlling traffic signal lights in accordance with a pretimed cycle, where the service requirements are extremely simple; but, in order to meet requirements of greater complexity, 45 more, less, or all of the supplemental equipment and wiring shown in Fig. 3 are needful.

Referring now to Fig. 4, it will be seen that the operating parts are the same as the corresponding parts indicated in Fig. 3, except that, instead of the spring 159 being so applied as to retain the arm 157 intermediate the contacts 65 and 66, as in Fig. 3, the spring 159' of Fig. 4 will tend to retain said arm in engagement with the one or the other of said contacts toward which it was last moved through cooperation of the pins 151' and 152' with the dog 154.

Associated with the traffic signal controller of Fig. 4, are the signal lamps 402 and 404; the lamp 402 giving a red or "stop" signal for traffic 60 in a certain lane, and a green or "go" signal for traffic in an intersecting lane; while the lamp 404 gives a green or "go" signal for said first named traffic lane and a red or "stop" signal for said intersecting lane.

65 The conductor 406 connects one terminal of the lamp 402 with contact 65, and the conductor 408 correspondingly connects lamp 404 with contact 66. The remaining terminals of lamps 402 and 404 are connected to supply source conductor 410, and supply source conductor 412 is connected to arm 157. It will therefore be evident that when the arm 157 engages contact 65, lamp 402 will be lighted, thereby giving a "go" signal aspect for traffic in one lane and a "stop" aspect 70 for traffic in another lane; and when the arm 157

is engaging contact 66, the opposite signaling aspects will be provided for the respective lanes.

A two-way switch comprising the arm 414 and the contacts 416 and 418, provide means whereby the controller may be adapted for operation either independently or subject to control of the contacts of a suitable master timer. Conductors 420 and 426 connect arm 414 with one of the contacts 64 and with supply source conductor 412, respectively; conductor 422 connects one of the contacts 63 with the contact 418 associated with the switch arm 414; conductor 270 connects the remaining ones of contacts 64 and 63 with one terminal of the motor M2; and conductor 424 connects the remaining terminal of said motor with the supply source conductor 410.

From the foregoing it will be apparent that if the switch arm 414 is positioned upon the contact 418, the motor M2 will operate continuously; if, however, it is desired that the operation of said motor shall be rendered responsive to a master controller, having periodically operable contacts such as shown at 68, the conductors 428 and 430 should be extended from such master controller contacts to the contacts 418 and 416, respectively, 25 associated with the switch arm 414, and said arm should be positioned upon contact 416.

The operation of a traffic signal controlling system such as that shown in Fig. 4, and just described, is as follows:

Assuming that the switch arm 414 is positioned upon its associated contact 418, and that contact arm 157 engages contact 66, the lamp of signal 404 will be lighted, and the motor M2 will rotate the shaft 119 until the pin 151' engages and moves 35 the dog 154 so as to carry the contact arm 157 away from the contact 66 and into engagement with the contact 65; whereupon the lamp of signal 404 will be extinguished and the lamp of signal 402 will be lighted.

40 Thereafter, continued rotation of shaft 119 will carry pin 152' into engagement with dog 154 and thereby cause contact arm 157 to be moved away from contact 65 and into engagement with contact 66, thus restoring the previous signal 45 aspect, and such cycle of operation will continue so long as energy is supplied from the current source.

As previously explained, the total length of the signaling cycle thus effected, will be determined 50 by the speed of rotation imparted to the shaft 119, and the division of such cycle between the period when the lamp of signal 402 is lighted and the period during which the lamp of signal 404 is lighted may be manually set, by changing the 55 angular displacement of the arms 151 and 152.

If connections are provided for operation in connection with a master timer, and operation of such type is desired, the switch arm 414 should be positioned in engagement with contact 416, 60 as a result of which the operation of motor M2 will be suspended whenever contacts 64 open (contacts 63 being then closed, as previously explained), unless and until the contacts 68 of the master timer are closed, whereupon actuation of 65 the controller for another operative cycle will be initiated, as well understood by those skilled in this art.

In order to effect control of traffic signal governing lamps in a manner which will provide for 70 conditions which are more complex than those to which a controller such as that of Fig. 4 is suited, a circuit controlling mechanism embodying all or any needed portion of the instrumentalities of the mechanism SC indicated in Figs. 1, 2, 3 75

and 5, should be associated with and made responsive to a timer mechanism, such as the mechanism CD.

The details of the mechanical structure of the circuit controlling mechanism SC will be best understood by referring to Fig. 2, in which an arrangement of parts is shown which corresponds generally with the disclosure of Figs. 1 and 3; but it will be noted that the solenoids E and J are shown in Fig. 1 as being both situated to the left of the cams there indicated, and in Fig. 3 as being both to the right of these cams, while in Fig. 2, in order to avoid distortion or obscuring of other parts, the solenoid E is shown to the right and the solenoid J to the left of the other parts.

The circuit controlling mechanism frame plates 15 and 16 are maintained in suitably spaced relation by the contact strips 76, 76' and 76'', which are electrically isolated therefrom by the insulating plates 77, 77. (See Fig. 1.) The frame plate 15 is secured to the panel 14 by means of the hinges 20, 20, so that the entire circuit controlling mechanism may be so swung as to carry the frame plate 16 away from the panel 14 and thereby afford convenient access to all portions of said mechanism. The latch 21 is secured to the panel 14 for engagement with the frame plate 16, to normally maintain same in snug engagement with said panel.

The motor M3 is suitably secured to the frame plates 15 and 16, and comprises the metal disc 32, which is fixed upon the shaft 34, to drive the gear 36 through the shaft 38, ratchet wheel 40, 35 ratchet dog 42, worm gear 44 and worm 46. The stationary magnet 52 and the adjustable magnet 54 are provided for driving the disc 32, said magnet 54 being adjustable with relation to said magnet 52 for the purpose of varying the speed of 40 rotation of disc 32 through manual setting of the pointer 56, which effects rotation of the pinion 58 and thereby moves the rack 60; the permanent brake magnet 62 being applied in a well-known manner.

45 The cam shafts 102 and 104 are driven by the gear 36, as diagrammatically indicated in Fig. 3, and as shown in greater detail in Fig. 2, where the gears 106 and 108 are fixed upon the shaft 102, and the gear 110 is fixed upon the shaft 104; 50 the gear 106 being engaged by the gear 36 and the gear 108 acting through the gear 110 to drive the shaft 104 at the speed of the shaft 102.

The cams 201, 202, 203, 204, 205, 206, 207, 208, 209, 210, 211, 212, 213 and 214 are mounted upon 55 the shaft 104 to be driven thereby, in a manner facilitating wide variations in the relative settings and periods of effectiveness thereof, as hereinafter more fully explained, in connection with Figs. 5 and 6.

60 The cams 217, 218, 221, 222, 223, 224 and 225 are correspondingly secured to shaft 102.

The contact finger 201' is operatively associated with the cam 201. Said finger being mounted upon an insulating strip 76, carried by the arm 65 72, which is, in turn, pivoted upon the rod 74. The free end of the contact finger 201' is situated adjacent the contact strip 76, and so that intended movement will effect closing and breaking of an electrical connection therebetween.

70 The spring 78 is so applied to the arm 72 as to urge movement of the finger 201' toward the strip 76. A follower 80, pivoted at 82, carries a roller 84 near the free end thereof, which roller 75 rides the cam 201, and the thrust rod 86 connects the follower 80 with the arm 72 so that

the rise of the cam 201 will cause the finger 201' to be moved away from the strip 76, and withdrawal of the raised portion of the cam 201 from the path of the roller 84 will permit the spring 78 to move the contact finger 201' into 5 electrical connection with the strip 76. The contact fingers 202', 203', 204', 205', 206', 207', 208', 209', 210', 211', 212', 213' and 214' being correspondingly associated with the cams 202, 203, 204, 205, 206, 207, 208, 209, 210, 211, 212, 213 and 10 214, respectively, and the fingers 209'' and 211'' being similarly associated with the fingers 209' and 211', respectively, so as to move therewith. The fingers 209'' and 211'' cooperate with the contact strip 76'', and the contact fingers 202', 15 204', 206', 208', 210', 212' and 214' correspondingly cooperate with the contact strip 76', while the remaining ones of the aforesaid contact fingers cooperate with the strip 76. The contact fingers 201', 203', 205', 207', 209', 211' and 213' 20 are carried by the rod 74, while the contact fingers 202', 204', 206', 208', 210', 212' and 214' are carried by the rod 74'.

The follower 80' is arranged for cooperation with the cam 218 in a manner corresponding to 25 that heretofore described in connection with follower 80, said follower being pivoted on the rod 82', and carrying the insulating strip 70' to which is secured the contact finger 218'. The contact strip 76''' is mounted in cooperative relationship with the finger 218', and the spring 78' is so applied to said finger that when the teeth of the cam 218 are not in effective relationship with the follower 80', the spring 78 will move the finger 218' into engagement with 35 the contact strip 76'''. The contact fingers 211', 225', 223', 222', 221' and 224' are correspondingly mounted and associated with said contact strip and with the cams 217, 225, 223, 222, 221 and 224, respectively. 40

It will be noted that, in the interests of clearness and simplicity, the representations of the various cams and their associated contacts in the diagrammatic representations thereof in Fig. 3 differ somewhat from the more specific representation of the form and arrangement of these parts in Fig. 2; correspondingly, the cooperating contact tips indicated in the more or less expanded isometric view of Fig. 2, correspondingly differ, for like reasons, from the proportions as 45 more accurately portrayed by Fig. 1. Likewise, Fig. 13 is merely illustrative of the various electrical circuits and no attempt is made to illustrate the parts in a mechanically operable form.

The rock shaft 162 is connected through the 55 arm 164 and link 166 to the core 168 of the solenoid J, a spring 170 being so applied to the arm 164 as to tend to move same in the direction which will withdraw the core 168 from the coil of the solenoid J, and the stop pins 172 and 174 are positioned in the path of movement of the arm 164 so that said pin 172 will limit the movement of the arm 164 in response to the spring 170, and said pin 174 will limit the movement of said arm in response to the pull of the core 168. 60

The arrangement of parts is such that upon effective energization of the solenoid J, the rock shaft 162 will be rotated in one direction approximately 90° and, thereafter, upon deenergization of said solenoid, said shaft will be rocked to a 70 like extent in the opposite direction.

The portions of the rock shaft 162 which are situated in the paths of the insulating strips 70 associated with the contact fingers 203' and 211' are so cut away that, when the shaft is in the 75

position which it occupies when solenoid J is deenergized, and the arm 164 is resting against the pin 172, said cut away portions will permit their associated contact fingers to move into engagement with the contact strips 76, but when solenoid J is energized, and said arm 164 has been moved into engagement with the stop pin 174, such cut away portions will be so moved with relation to the respective insulating strips that their associated contact fingers will be held in spaced relationship from the contact strip 76.

Portions of the rock shaft 162 which are situated in the paths of the insulating strips 70 associated with the contact fingers 201', 205', 209' and 213', are correspondingly cut away, except that the portions associated with the last named contact fingers are so angularly positioned upon the shaft as to permit their associated contact fingers to be brought into connection with the contact strip 76 only while said shaft is in the position which it occupies when the arm 164 has been moved into engagement with the stop pin 174. The insulating strip 70 associated with contact finger 201' is so formed as to permit said contact finger to move into connection with the contact strip 76 irrespective of the positioning of said shaft 162.

From the foregoing, it will be apparent that so long as the solenoid J remains deenergized, the rock shaft 162 will be so positioned as to prevent contact fingers 201', 205', 209', 209'' and 213' from establishing connections with contact strip 76, while permitting (subject to the positioning of their associated cams) contact fingers 203', 207', 211' and 211'' to connect with their cooperating contact strips; and so that, when said shaft 162 has been rotated responsive to energization of solenoid J, contact fingers 201', 205', 209', 209'' and 213' will be permitted (subject to the positioning of their associated cams) to move into connection with their cooperating contact strips while corresponding connections will be prevented as to contact fingers 203', 211' and 211''.

Each of the cam followers 80 carries, at the free end thereof, a projection 80'' for cooperation with the half-round rock shaft 176; the relative formation of the parts being such that when the flattened portion of said shaft is disposed in plane parallel of said projections 80'', said followers will be permitted to move in accordance with the contours of their respectively associated cams, and so that when said shaft has been suitably rotated, said followers will be supported so as to prevent such movement thereof as would permit their respectively associated contact fingers from moving into connecting relationship with their cooperating contact strips. The shaft 176 has fixed thereon an arm 164' which is connected through the link 166' to the core 168' of the solenoid E. Stop pins 172' and 174' are provided for limiting the angular movement of said arm 164', and the spring 170' is applied for urging movement of said arm in the direction opposite to that imparted thereto by excitation of the solenoid E, so that the rock shaft 176 will be subject to actuation by the solenoid E in a manner corresponding to the actuation of the rock shaft 162 by the solenoid J, as hereinbefore described.

As most clearly shown in Fig. 3, the pedestrian memory relay P comprises the stationary contacts 22 and 24 and the contacts 26 and 28 movable responsive to energization of said relay into

engagement with said respective stationary contacts.

The flashing service control relay N comprises the stationary contacts 111, 112, 114 and 116 and the movable contacts 113, 115 and 117. Upon energization of said relay, the contact 113 is movable into engagement with contacts 111 and 112, the contact 115 is movable into engagement with contact 114, and the contact 117 is movable away from contact 116.

In order to more clearly indicate the application of the traffic signal controlling mechanism thus far described to a group of traffic signal lamps, and a group of traffic responsive contacts, there is shown at S, in a conventionally diagrammatic manner, the green (G, G, G, G), amber (A, A, A, A) and red (R, R, R, R) traffic signal lamps for governing traffic in an arterial highway and an intersecting highway; the "right-turn-indicating" lamps 48 and 50 being associated with the lamp groups provided for the main or arterial highway. As representative of traffic responsive contacts, the four pedestrian push buttons B, B, B, B are indicated as if at respective corners of the intersection.

There is also indicated at T a master timer comprising an electric motor M1, a cam 230 rotated by said motor through the reduction gears 232 and 234, for maintaining the contacts 236 in separated relationship during all but a comparatively small portion of a cycle of the rotation of said cam; an adjustable resistance 238 being provided for varying the speed of the motor M1, an adjustable resistance 240 for regulating the speed of the motor or motors of local traffic signal controllers, such as the motor M2, and switches 242 and 253 for suspending the normal routine cycle of response of the signal lamps to the rotation of the cams of the signal circuit controlling mechanism SC and, in one instance, substituting therefor an intermittent or flashing amber aspect, as will be hereinafter more fully explained.

The electrical connections between the parts thus far described are as follows:

The supply source conductor 250 connects with the conductors 252 and 254, and the supply source conductor 256 connects with the conductor 258 and one terminal of the adjustable resistance 238. The conductor 252 extends from supply source conductor 250 to one terminal of the magnet of relay N, and the conductor 260 connects the conductor 252 to one terminal of the motor M2. The conductor 254 connects one terminal of the motor M1 to conductor 250 and conductor 262 connects the other terminal of said motor M1 to the remaining terminal of the adjustable resistance 238. The conductor 258 connects supply conductor 256 through closed switch 253 to contacts 117 of relay N, the conductor 264 serially includes the switch 242 and connects the conductor 258 with the other terminal of the magnet of relay N; the conductor 266 connects the conductor 258 to one of the contacts 236 and the other of said contacts is connected through conductor 268 with one of the contacts 63; the other of said contacts 63 being connected through the conductor 270 with the remaining terminal of the motor M2 and with one of the contacts 64. The other of said contacts 64 is connected through the conductor 272 to one terminal of the adjustable resistance 240 at the master timer T, the other terminal of said resistance being connected to conductor 258.

Conductors 274, 276 and 278 connect the sta-

tionary members of contacts 66, 65 and 67 with contact fingers 222', 221' and 223', respectively.

The conductor 280 extends from contact arm 157 to one terminal of motor M3 serially including adjustable resistance 282. The remaining one of the contacts 67, and the contact fingers 224' and 225' are also connected to said conductor 280. The conductor 284 connects conductor 280 with the contact 114 of relay N, and the conductor 286 connects the contact strip 76''' with the contact strip 76''. The conductor 288 connects the contact strip 76' with the contact strip 76; the conductor 296 connects the contact strip 76 with the contact strip 76''; the conductor 290 connects the contact finger 218' with the contact 113 of relay N, and the conductor 292, which serially includes the switch 294, connects the conductor 290 with the contact finger 217'.

20 The supply source conductors 300 and 302 may derive energy from the same source as the supply source conductors 250 and 256, or from a different source, as may be in any instance more convenient.

25 The supply source conductor 300 connects with one terminal of each of the signal lamps R, R, R, R; A, A, A, A; G, G, G, G; 48 and 50; the conductor 304 connects the conductor 300 with the remaining terminal of the motor M3, the switch 306 being serially included in said conductor in close proximity to this motor; and the conductor 308 connects the conductor 304 with an end of the winding of solenoid J. The conductor 310 connects one terminal of the winding of relay P to the supply source conductor 300, and the conductor 312 connects the other terminal of said winding to the contact 28; said other terminal being also connected through the conductor 314 to the conductor 316 which connects to one terminal of each of the pedestrian push buttons B, B, B, B; the remaining terminals of said buttons being interconnected by the conductor 318 which is, in turn, connected through the conductor 320 with the supply source conductor 302.

45 The supply source conductor 302 extends to the contact strip 76, and the conductor 322 connects said conductor 302 with the contact 115 of relay N. The conductor 324 connects the contact finger 201' with one terminal of each of the stop lamps R, R provided for the arterial highway at S, and the conductor 326 connects the contact finger 202' with the conductor 324. The contact fingers 203' and 204' are correspondingly connected through conductors 328 and 330 with the green "go" lamps for said arterial highway. Correspondingly alternative current paths are provided from the amber lamps A, A for the arterial highway to the contact 111 of relay N and to the contact fingers 205', 207' and 209' through conductors 334, 336 and 338. The conductor 340 connects the contact finger 206' with the remaining terminals of the "go" signal lamps G, G for the intersecting highway. The conductor 342 connects the contact finger 208' with the remaining terminals of the "stop" lamps R, R for the intersecting highway. The conductor 344 connects the remaining terminals of the "caution" or amber lamps A, A, for the intersecting highway, with the contact finger 209' and with

70 the contact 112 of relay N. The conductor 345 connects the contact finger 211' with the contact 24 of relay P, and the conductor 346 connects the conductor 344 with the contact finger 210'. The conductor 348 connects the contact finger 211' with the remaining terminals of the right-

turn arrow lamps 48 and 50, and the conductor 350 connects the contact finger 214' with the conductor 348. The conductors 352 and 354 connect the contact fingers 212' and 213' with the contacts 22 and 28 of the relay P, respectively; and the conductor 356 connects the remaining end of the winding of the solenoid J with the conductor 354. The conductor 358 connects one end of the winding of the solenoid E with the conductor 252, and the remaining end of said winding is connected through the conductor 360 to the contact 116 of relay N.

When the various parts are positioned as shown in Fig. 3, current flow is effective through paths as follows:

15 From the supply source conductor 250, through conductor 254, motor M1, conductor 262 and adjustable resistance 238 to supply source conductor 256; thus causing the motor M1 to drive the cam 230 at desired speed, as determined by the adjustment of the resistance 238.

20 From the supply source conductor 250, another current path is effective through conductor 252 to conductor 260, thence through motor M2, through conductor 270, through closed contacts 64, 25 through conductor 272 and adjustable resistance 240, to conductor 258, and thence through conductor 258 and closed switch 253 to supply source conductor 256. Because of the establishment of this current path, motor M2 will drive the shaft 30 119, and the parts carried thereby, at such speed as may be determined by the adjustment of the resistance 240, at the master timer T.

25 Still another current path is established from the supply source conductor 250, through conductors 252 and 358, to and through the winding of the solenoid E, thence through conductor 360, contacts 116 and 117, and conductor 258, including closed switch 253, to the supply source conductor 256.

30 From the supply source conductor 300, a current path is established through conductor 304, closed switch 306, motor M3, adjustable resistance 282, conductor 280, contact finger 224', contact strip 76''', conductor 286, contact strip 76', conductor 288, and contact strip 76, to the supply source conductor 302, thus causing the motor M3 to drive the cam shafts 102 and 104 at such speed as is determined by the manual adjustment of the resistance 282.

35 For effecting the display of the "right-turn" signal by lighting the lamps 48 and 50, a current path is established from the supply source conductor 302, through contact strip 76, thence through parallel current paths one of which is through the contact finger 211' to conductor 348 and the other of which comprises conductor 288, contact strip 76', contact finger 214' and conductor 350 to said conductor 348, thence through said lamps in parallel to the supply source conductor 300.

40 The red "stop" lamps R, R for the intersecting highway, are lighted through a current path extending from the supply source conductor 302, through contact strip 76, finger 208', conductor 342 and through said lamps in parallel to supply source conductor 300.

45 Correspondingly, the green "go" lamps G, G for the arterial highway are lighted through a current path extending from the supply source conductor 302, through contact strip 76, from which parallel current paths are provided, one of which paths comprises the contact finger 203' and conductor 328 and the other of which comprises the conductor 288, contact strip 76', con-

tact finger 204' and conductor 330 to said conductor 328, thence through said lamps in parallel to the supply source conductor 300.

Because of the establishment of the foregoing 5 current paths, the motor M1 will operate at a speed as determined by resistance 238; the motor M2 will operate at a speed as determined by resistance 240; the motor M3 will operate at a speed as determined by resistance 282; the rock 10 shaft 176 will be positioned, responsive to the energization of the solenoid E, so as to permit movement of the contact fingers which are functionally associated therewith, in accordance with the contours of their respective cams; the rock shaft 162 will be positioned, due to non-energization 15 of the solenoid J, so as to permit the contact fingers 203', 211' and 211'', as well as contact finger 207', to move into engagement with contact strip 16; and, at the same time, preventing movement to such a circuit closing position of 20 any of the other contact fingers functionally associated with said rock shaft 162; the relay N will be deenergized, so that the contact 113 will be withdrawn from the contacts 111 and 112, the contact 115 will be withdrawn from the contact 25 114 and the contact 117 will engage the contact 116; the relay P will be deenergized so that its contacts 26 and 28 will be separated from the contacts 22 and 24, respectively; the right-turn 30 lamps 48 and 50, and the green "go" lamps G, G for the arterial highway will be lighted, as will be the red "stop" lamp R, R for the intersecting highway; and the traffic responsive contacts B, B, B, B will stand open.

In order to provide intended operative results, the adjustment of the resistance 282 should be such that the motor M3 will effect an intended cycle of movement (which, with the arrangement shown, would be one revolution of the cam shafts 102 and 104) in a time somewhat less than any intended cycle of rotation of the shaft 119, for a reason which will be hereinafter more fully explained.

Correspondingly, the resistance 240 should at 45 all times be so adjusted that the motors M2 of all of the local traffic signal controllers which are arranged in responsive relationship to the master timer T shall move through their intended operating cycle in a time not greater than, and preferably somewhat less than that of the operating cycle of the cam 230 of said master timer.

The adjustable arms 149, 151, 152 and 153 should be so relatively set as to provide desired 50 relative characteristics of the various signal cycle component periods as will be hereinafter more fully explained. The switch 242 should stand open and the switches 253 and 306 should stand closed.

Assuming that all parts have been suitably adjusted and set, as just pointed out, the operation 60 of the apparatus and system indicated by Fig. 3 will be as follows: operation of motor M3 will cause rotation of shafts 102 and 104 until the raised portion of cam 225 is withdrawn, permitting contact finger 225' to move into connection with strip 76'', thus providing a current path in parallel with that rendered effective by connection of contact finger 224' with said strip; thereafter, the ensuing rotation of shaft 102 will cause the raised portion of cam 224 to move contact finger 224' away from contact strips 76'', whereupon, the further rotation of shaft 102 will bring another raised portion of cam 225 into engagement with contact finger 225', so as to move same away from strip 76''' and, thus interrupt

the energizing current path for motor M3, causing same to come to rest.

During the rotation of the shaft 102 and 104 just referred to, and at the time of (or, preferably slightly before) such separation of contact 5 225' from strip 76''', the raised portion of cam 221 will be withdrawn so as to permit contact finger 221' to move into connection with strip 76''', thus making provision for re-establishment of a driving current path for said motor M3, responsive to rotation of shaft 119 of timer mechanism CD.

During the signal periods rendered effective, incidental to activities of the signal circuit controlling mechanism SC thus far described,—the 15 activities of the timer mechanism CD and of the master timer T include the following:

The motor M2 continued to drive the shaft 119 in clockwise direction, as viewed in Fig. 3, until the raised portion of cam 131 had effected closure of contacts 63, and the raised portion of cam 132 had, immediately thereafter been withdrawn so as to permit separation of contacts 64. Motor M1 of master timer T would, at this time, have rotated cam 230 a sufficient distance to 25 nearly or quite withdraw the raised portion thereof, so that at or soon after attainment of the stage of the operative cycle of the circuit controlling mechanism CD just referred to, the contacts 236 will be permitted to close; so that, upon 30 interruption of the previously described current supply path for motor M2 due to separation of contacts 64, an alternative current path will be provided from conductor 250, through conductors 252 and 260, through motor M2, conductor 270, contacts 63, conductor 268, contacts 236, conductors 266 and 258 (including switch 253) to supply source conductor 256, in the event that contacts 236 had then been permitted to close.

If, at the time when contacts 64 open, as just 40 referred to, the cam 230 has not yet permitted contacts 236 to close, motor M2 will be brought to rest until such time as contacts 236 next close.

From the foregoing, it will be evident that such local controllers as are associated with the master 45 timer T, in a manner such as indicated in Fig. 3, will be kept "in step" or in desired cyclic relation with one another through the synchronizing effect of said master timer.

During the ensuing rotation of shaft 119, cam 50 132 will next close contacts 64, and thereby establish the previously described supply current path for motor M2, and the raised portion of cam 131 will be withdrawn so as to permit contacts 63 to again open.

The ensuing rotation of shaft 119 by motor M2 will cause pin 151' to be carried into engagement with dog 154, swinging same so as to carry contact arm 157 into engagement with contact 60 65: thus establishing a driving current path for restarting motor M3 as follows: from supply source conductor 300, through conductor 304 and switch 306 to one terminal of motor M3, through said motor and its associated resistance 282, through conductor 280, contact arm 157, contact 65 65, conductor 276, contact finger 221', contact strip 76''', conductor 286, contact strip 76', conductor 288 and contact strip 76 to supply source conductor 302.

As a result of the establishment of such current path, motor M3 will rotate shaft 102 and thereby remove the raised portion of cam 225 so as to permit contact finger 225' to move into connection with contact strip 76'''. Current for driving motor M3 will thus be supplied until the 70 75

next raised portion of cam 225 engages contact finger 225', irrespective of continued engagement of contact 65 by contact arm 157 of timer mechanism CD.

5 In the course of the rotation of shaft 102, prior to the engagement of contact finger 225' by such next raised portion of cam 225, as just referred to, cam 204 will cause contact finger 204' to move away from contact strip 76', and thus 10 interrupt one of the two parallel current paths provided for the current supply to the green "go" lamps G, G for the arterial highway; but, inasmuch as contact finger 203' in the other one of the parallel paths remains closed, such lamps 15 will continue to burn.

15 At or about the time that contact finger 204' is thus raised, cam 212 will momentarily permit contact finger 212' to move into connection with contact strip 76' for a purpose which will be hereinafter more fully explained. Further rotation 20 of shaft 102 will cause cam 214 to lift contact finger 214' away from contact strip 76', thus breaking one of the parallel paths through which current is supplied to the green arrow lamps 48 and 50; but inasmuch as the other parallel current path through contact finger 211' remains closed, these lamps will, at this time, continue to burn.

25 Following the accomplishment of the foregoing results, continued rotation of shaft 102 will withdraw the raised portion of cam 222, so as to permit contact finger 222' to move into connection with contact strip 76''' and, thereafter, such next raised portion of cam 225 will lift contact finger 225' away from contact strip 76''' and thus again bring motor M3 to rest.

30 During the ensuing rotation of shaft 119, the pin 152' is carried into engagement with the dog 154, swinging same so as to carry contact arm 157 into engagement with contact 66, thereby 35 establishing a driving current path for motor M3 from supply source conductor 300, through conductor 304 and closed switch 306 to and through motor M3 and its associated resistance 282, through conductor 280, contact arm 157, contact 40 finger 66, conductor 274, contact finger 222', contact strip 76''', conductor 286, contact strip 76', conductor 288, and contact strip 76 to supply source conductor 302.

45 As a result of establishment of such current path, motor M3 will rotate shaft 102 and thereby remove the raised portion of cam 225 permitting contact finger 225' to move into engagement with contact strip 76''' and thereby provide for supplying driving current for motor M3 until the 50 next raised portion of cam 225 engages contact finger 225', irrespective of continued engagement of contact 66 by contact arm 157 of timer mechanism CD.

55 During the rotation of shaft 102, just referred to, shaft 104 will be so turned as to withdraw the raised portion of cam 207 and thereby permit contact finger 207' to connect with contact strip 76, thus establishing a current path for lighting the arterial highway amber lamps A, A from supply source conductor 302 through contact strip 76, contact finger 207', conductors 336 and 334 and said lamps in parallel to supply source conductor 302.

60 Movement of shaft 104, such as thus far described, will also cause the raised portion of cam 203 to move contact finger 203' away from contact strip 76 and thereby effect extinguishment of the green "go" lamps G, G for the arterial highway, by interrupting the current path

through which they had been lighted, as hereinbefore more fully explained.

65 The rotation of shaft 104 then ensuing will cause cams 202, 206 and 214 to permit their associated contact fingers 202', 206' and 214', respectively, to close, and cams 207 and 208 to lift their associated contact fingers 207' and 208', respectively; all of which changes will occur at or about the same time.

70 When contact finger 202' thus moves into engagement with strip 76', the red "stop" lamps R, R for the arterial highway will be lighted through a current path from supply source conductor 302, through contact strip 76, conductor 288, contact strip 76', contact finger 202', conductors 326 and 324, and said lamps in parallel, to supply source conductor 300.

75 When contact finger 206' connects with contact strip 76', as just referred to, the green "go" lamps G, G for the intersecting highway will be lighted through a current path from supply source conductor 302, through contact strip 76, conductor 288, contact strip 76', contact finger 206', conductor 340, through said lamps in parallel, to supply source conductor 300.

80 When contact finger 214' thus connects with contact strip 76', the parallel path is restored through which current had been supplied to the green arrow lamps 48 and 50.

85 The withdrawal of contact fingers 207' and 208' from contact strips 76 and 76', respectively, as just described, resulted in opening the current paths previously effective therethrough, and thus resulted in extinguishment of the amber lamps A, A for the arterial highway and the red "stop" lamps R, R for the intersecting highway.

90 Following the accomplishment of the foregoing results, the ensuing rotation of shaft 102 will withdraw the raised portion of cam 223 so as to permit contact finger 223' to move into connection with contact strip 76''' and, thereafter, the next raised portion of cam 225 will lift contact finger 225' away from contact strip 76''' and thus again bring motor M3 to rest.

95 During the rotation of shaft 119 following actuation of dog 154 by pin 152', the pin 153' is carried into engagement with the arm 155, swinging same about shaft 156 so as to close contacts 67 and thereby establish a driving current path for motor M3 from supply source conductor 300, through conductor 304 and closed switch 306, through motor M3 and its associated resistance 282, through conductor 280, contact 67, conductor 278, contact finger 223', contact strip 76''', conductor 286, contact strip 76', conductor 288, and contact strip 76 to supply source conductor 302.

100 As a result of the establishment of such current path, the motor M3 will rotate the shaft 102 and thereby remove the raised portion of cam 225, thus permitting contact finger 225' to move into connection with contact strip 76'''. Current for driving motor M3 will be thus supplied through the path just traced until the next raised portion of cam 225 engages contact finger 225', irrespective of continued closure of contacts 67 of the timer mechanism CD. When the raised portion of cam 225 has engaged the contact finger 225', the parts of Fig. 3 will be positioned as therein shown; the shafts 102 and 104 having completed one cycle of normal operation.

105 In the course of the rotation of the shaft 102 prior to the engagement of the contact finger 225' by the next raised portion of cam 225, as just referred to, cam 206 will cause contact finger

206' to move away from contact strip 76', thereby interrupting the current path provided for supplying the green "go" lamps G, G for the intersecting highway.

5 Simultaneously with the separation of contact finger 206' from contact strip 76', the raised portion of cam 210 will be withdrawn so as to permit connection between contact finger 210' and contact strip 76', thus establishing a current path 10 for lighting the intersecting highway amber lamps A, A from supply source conductor 302, through contact strip 76, conductor 288, contact strip 76', contact finger 210', conductors 346 and 344, and through said lamps in parallel, to supply source conductor 300.

15 Continued rotation of shaft 104 will next cause the raised portion of cam 210 to move contact finger 210' away from contact strip 76' and thereby effect extinguishment of the amber 20 lamps A, A, of the intersecting highway.

25 Simultaneously with the separation of contact finger 210' from contact strip 76', the raised portion of cam 202 will cause contact finger 202' to move away from contact strip 76' and thereby 30 cause extinguishment of the red "stop" lamps R, R for the arterial highway; and, the raised portions of cams 203, 204 and 208 will be withdrawn, thus permitting contact fingers 203', 204' and 208' to connect with their respectively associated contact strips.

35 When contact fingers 203' and 204' thus move into connection with contact strips 76 and 76', respectively, the green "go" lamps G, G for the arterial highway will be again lighted through parallel current paths comprising conductors 328 and 330, as hereinbefore more fully explained.

40 Correspondingly, when contact finger 208' thus moves into connection with contact strip 76, the red "stop" lamps R, R for the intersecting highway will be lighted through a current path including conductor 342.

45 Throughout the cycle of normal operation for shafts 102 and 104 as just completed, contact fingers 201', 205', 209', 209'' and 213' are maintained out of effective engagement with their associated contact strip 76, through positioning of rock shaft 162 resultant from deenergization of solenoid J.

50 If, at any time in the cycle, one of the pedestrian push buttons B, B, B, B is closed, pedestrian memory relay P will be energized, through a current path from supply source conductor 302, through conductors 320 and 318, through the closed push button, through conductors 316 and 55 314, through winding of relay P and conductor 310, to supply source conductor 300. Upon establishment of this current path, contacts 26 and 28 will be brought into engagement with contacts 22 and 24, respectively. Such engagement of 60 contact 24 by contact 28 establishes a holding path from supply source conductor 302, through contact strip 76, conductor 296, contact strip 76'', contact finger 211'', conductor 345, contacts 24 and 28, conductor 312, winding of relay P and 65 conductor 310 to supply source conductor 300.

70 Following energization of relay P, as just referred to, the cycle of control of the highway signal lamps at S will continue, as hereinbefore more fully explained, until the raised portion of cam 212 is withdrawn, thereby permitting contact finger 212' to move into connection with contact strip 76'; whereupon a current path for energization of solenoid J will be established from supply source conductor 302, through contact 75 strip 76, conductor 288, contact strip 76', con-

tact finger 212', conductor 352, contacts 22 and 26, conductors 354 and 356, winding of solenoid J, and conductors 308 and 304 to supply source conductor 300.

When the solenoid J is thus energized, rock 5 shaft 162 will be so rotated as to permit contact finger 213' to move into connection with contact strip 76, and, thereupon, to move contact fingers 211' and 211'' away from contact strips 76 and 76'', respectively.

10 Such engagement of contact strip 76 by contact finger 213' provides a lock-up path for solenoid J which is exclusive of contact finger 212' and contacts 22 and 26, as follows: from supply source conductor 302 through contact strip 76, contact finger 213', conductors 354 and 356, winding of solenoid J, conductors 308 and 304 to supply source conductor 300. Such separation of contact finger 211'' from contact strip 76'' breaks the holding path for relay P, as hereinbefore described, resulting in its deenergization and in separation of contacts 26 and 28 from contacts 22 and 24, respectively.

15 From the foregoing, it will be evident that the parts should be so adjusted and related that contact finger 213' will connect with contact strip 76 before contact 26 moves away from contact 22, following interruption of the energizing current path of relay P.

20 A further result of the rotation of rock shaft 30 162 which is incidental to energization of solenoid J, is the presentation of cut away portions of said shaft so as to permit contact fingers 201', 205', 209' and 209'' and, as already referred to, contact finger 213', to move into connection with 35 their associated contact strips 76 and 76'' whenever permitted so to do by their respectively associated cams; and such movement of said rock shaft further withdraws cut away portions thereof so as to provide support, independent of their associated cams, for contact finger 203', in addition to the support of contact fingers 211' and 211'' previously referred to.

25 When rock shaft 162 has been thus rotated, the raised portions of cams 201 and 209 will prevent their respectively associated contact fingers from moving into connection with their cooperating contact strips, but the raised portion of cam 205 will be then withdrawn so that contact finger 205' will immediately move into engagement with 50 contact strip 76, and the same will be true with respect to cam 213 and contact 213', as already mentioned. At the same time, cam 204 will move contact finger 204' away from contact strip 76', thus effecting extinguishment of the green "go" 55 lamps G, G for the arterial highway.

60 The connection of contact finger 205' with contact strip 76, just referred to, establishes a current path for lighting the amber lamps A, A for the arterial highway from supply source conductor 302, through contact strip 76, contact finger 205', conductor 334, and said lamps in parallel, to the supply source conductor 300.

65 From the foregoing, it will be apparent that, at or immediately after rotation of rock shaft 162 responsive to energization of solenoid J, right-hand arrow signal lamps 46 and 50 and amber lamps A, A for the arterial highway, and red "stop" lamps R, R for the intersecting highway will be lighted.

70 Ensuing rotation of cam shaft 104 will next withdraw raised portions of cams 201 and 209, thus permitting their associated contact fingers 201' and 209' to move into connection with their associated contact strip 76. Contact finger 201' 75

thus establishes a current path for red "stop" lamps R, R for the arterial highway, from supply source conductor 302 through contact strip 76, contact finger 201', conductor 324, and said lamps in parallel, to supply source conductor 300; and contact finger 209' thus establishes a current path for amber lamps A, A for the intersecting highway from supply source conductor 302, through contact strip 76, contact finger 209', conductor 344 and said lamps in parallel to supply source conductor 300.

At or about the time that contact fingers 201' and 209' are permitted to connect with contact strip 76, as just described, the raised portion of cam 214 moves contact finger 214' away from contact strip 76', thus interrupting the second one of the parallel paths through which right-turn arrow lamps 48 and 50 had been previously lighted, thereby effecting the extinguishment of 20 said lamps. (The other parallel path having been interrupted when contact finger 211' was moved away from contact strip 76 by rock shaft 162.)

From the foregoing it will be seen that the right-turn arrow lamps 48 and 50 and all of the 25 green "go" lamps G, G, G, G will now be extinguished, and that the red "stop" lamps R, R, R, R and the amber lamps A, A, A, A for both highways will now be lighted; thus providing a 30 signaling aspect the presentation of which constitutes what may be termed "a pedestrian period", by indicating that all vehicular movements into, around or across the intersection shall cease, and that pedestrian movements may 35 freely proceed within the area of the intersection.

Following accomplishment of the results just described, shafts 102 and 104 will be rotated so as to cause one of the raised portions of cam 225 to lift contact finger 225', thus discontinuing the 40 current supply for motor M3 unless and until such supply is continued or resumed through the operation of timer mechanism CD, whereupon current supply for said motor M3 will be restored and rotation of the shafts 102 and 104 will proceed as hereinbefore more fully explained.

Such continuing rotation of shaft 104 will, at or about the same time, withdraw raised portions of cams 202, 206 and 214 and will present raised portions of cams 205, 207, 208, 209 and 213; although the presentation of the raised portion of 50 said cam 213 will be but momentary in character.

As a result of the cam actions just described, contact finger 213' will be moved away from contact strip 76, thereby interrupting the current path previously described for energization of solenoid J, whereupon rock shaft 162 will be rotated to its normal position by the urge of spring 170, thereby withdrawing the cut away portions thereof so as to render unresponsive to their respective cams the contact fingers 201', 205', 209' and 213'; while rendering responsive to their respective cams the contact fingers 203', 211' and 211'.

Resultant from restoration to normal position 65 of rock shaft 162, and to the movement of the various cams as just referred to, contact fingers 201', 205', 208' and 209' will move to open circuit position, thereby interrupting the current paths previously effective therethrough; thus terminating the "pedestrian period". Contact fingers 202', 206' and 214' will, at the same time, be permitted, by the contour of their respectively associated cams, to move to closed circuit position, thereby establishing the current paths controlled thereby. 70

75 In this connection it will be noted that, although

rotation of rock shaft 162 to restored position brought a cut away portion thereof in effective relation to contact finger 203', the cam associated with this contact finger prevented its immediate closure.

From the foregoing it will be seen that the right-turn arrow lamps 48 and 50, and the green "go" lamps G, G for the intersecting highway, will be lighted, and that the red "stop" lamps R, R for the arterial highway will continue to burn 10 because the newly established path through contact finger 202' serves as a substitute for the interrupted path through contact finger 201'.

From this point on, the operative cycle of the parts will continue as in the "normal" or "non-pedestrian period" cycle hereinbefore more fully 15 described.

In instances where one of the push buttons B, B, B is initially actuated at a stage in the cycle subsequent to movement of contact finger 212' to closed circuit position, relay P will energize and be maintained in "locked-up" condition until said contact finger moves to closed position in the course of the next succeeding cycle. A so-called "memory" feature is thus provided 25 as to such actuation of any of said push buttons as may occur; to the end that, when the system has been displaying a cycle or cycles of signal periods not including a "pedestrian period", operation of any one of the push buttons B, B, 30 B, B will cause the system to effect a cycle of operation including a full pedestrian period upon the next occasion when it is possible for it to properly do so. On the other hand, operation of any of such push buttons during that portion of a 35 "pedestrian period" in which pedestrian movement is permitted in the intersection, will not result in the relay P being left locked up; and therefore will not cause a repetition of the pedestrian cycle, because the locking current path for this relay is now interrupted at contact finger 40 211'; in fact, it is evident that the operation of any of such push buttons B, B, B, B at a time when relay P is in "locked-up" condition, or during energization of solenoid J resultant from any 45 previous energization of relay P, will not result in establishment of a cycle having a "pedestrian period", supplemental to the cycle already or about to be rendered effective.

From the preceding description of a cycle comprising normal traffic periods, and which may 50 therefore be termed "a normal cycle", and a cycle comprising a pedestrian period (and which may therefore be termed a "pedestrian cycle") it will be apparent that "stop" and "go" periods are provided for the arterial highway and for the intersecting highway, by both of these types of cycles; but, in the instance of the pedestrian cycle, the "go" period for the arterial highway is shortened, and a "pedestrian period" is added, which occupies 55 60 the time deducted from the normal arterial "go" period.

The characteristics of operating cycles, under settings and operations as hereinbefore more fully described, are graphically indicated by the chart 65 of Fig. 7, as to a "normal cycle" which does not include a pedestrian period, and in Fig. 8 as to a "pedestrian cycle" which does include such a period.

The representation of a normal cycle in Fig. 7 70 includes three stripes in the upper portion thereof, the first of which is lined to represent the lighting of the green or "go" lamp for the arterial highway, the second is lined to represent the lighting of the amber lamp for giving warning of an 75

impending change from "go" to "stop" (such amber periods being sometimes termed "clear" or "clearing" periods) and the third stripe is lined to represent the lighting of the red or "stop" lamp for the arterial highway. Associated with these three stripes is an indication representative of the continuous effectiveness of the "right-turn" green arrow signal.

In the lower portion of this chart, there are three stripes which correspondingly indicate the concurrently effective "go", "clear" and "stop" signal aspects for the intersecting highway.

The representation of a pedestrian cycle in the chart of Fig. 8 correspondingly indicates, in the upper portion thereof, the signal aspects affecting the arterial highway, and, in the lower portion, those affecting the intersecting highway.

With the various portions of the equipment set and adjusted as hereinbefore more fully described, should it be desired to, upon any occasion, increase the time allotted to the display of the green lamp or "go" signal for the arterial highway, without altering the duration of any of the other periods, it is evident that the entire cycle length should be increased to the desired extent; and, to this end, the resistance 238 should be so adjusted that the time required for one revolution of the cam 230 will be increased to the extent to which it is desired to increase the time occupied by the total cycle as well as that occupied by that portion of the cycle which is allotted for traffic movement on the arterial highway.

If it is desired to increase the times allotted to the intersecting highway green lamp or "go" signal period as well as to the pedestrian period, without appreciably altering the time allotted to the arterial highway green light or "go" period effective during a pedestrian cycle,—the resistance 240 and 238 should both be adjusted so that the intervals required for a revolution of the shaft 119 and for that of the cam 230, respectively, would be increased to a suitable extent; provided there had been previously effected a suitable relative setting of arms 151 and 153.

If it is desired to increase the arterial highway "go" period, the intersecting highway "go" period and the pedestrian period (when in effect), the resistance 240 should be adjusted so as to retard the rate of movement of the shaft 119, to the extent required to give the added time for the intersecting highway "go" and the pedestrian periods, and the resistance 238 should be adjusted to retard the rotation of the cam 230 to an extent corresponding to the retardation of the shaft 119, in addition to retardation representative of the amount of extension desired for the arterial highway "go" period. Thus, if the increase in time desired other than for the arterial highway is 10 seconds and that desired for the arterial highway is 20 seconds, the time required for one revolution of the cam 230 should be increased 30 seconds.

If it is desired to decrease the durations of the periods just referred to, this can be accomplished by corresponding adjustments of the resistances 238 and 240 in the opposite direction; subject, however, to the limitations that one revolution of the shaft 119 should in every instance require as much time (and preferably more time, in order to provide a factor of safety) than one revolution of the shafts 102 and 104; and, correspondingly, one revolution of cam 230 should occupy as much or slightly more time than one revolution of shaft 119.

It will, of course, be evident that, if desired,

the adjustment of resistance 238 could be such that every other closure of contact 236 would occur during an open circuit period of contact 63, to the end that, when the master timer T drives the cam 230 at a speed which would give one rotation of said cam in substantially less time than that occupied by one revolution of the shaft 119 of the timer mechanism CD, the effect would be substantially the same as if the cam 230 were being rotated at one-half the speed.

It will also be noted that the changes in operating characteristics thus far described are based upon an assumption that the duration of the amber so-called "change" or "clearing" periods would be unaffected by changes in the lengths of other periods. Such an arrangement is considered desirable, under most circumstances, inasmuch as the time required for clearing vehicular movements from a given intersection, following a "go" period for one highway or the other, is unlikely to require change incidental to changes in the "go" period themselves, such as may be desirable because of different densities of traffic during various portions of the day. If, however, it is desired to lengthen the amber lamp or "clearing" periods, this can be accomplished by altering the adjustment of resistance 282, so as to cause the motor M3 to operate more slowly when longer amber "clearing" periods are desired and more rapidly when shorter amber "clearing" periods are desired.

As hereinbefore indicated, a plurality of traffic signal controllers, such as that indicated in Figs. 1, 2 and 3, may be associated with a single master timer, as, for example, master timer T of Fig. 3. Furthermore, it is evident that the operating characteristics of all such local traffic signal controllers thus associated with a given master timer may be simultaneously revised from such master timer, within certain limits, as to durations of "go" and "stop" periods for both the arterial and intersecting highways and for pedestrian periods; however, the durations of the amber lamp "clearing" periods at the various local controllers are varied by suitable adjustments of the resistance 282 thereat to suit the conditions existing at the particular intersections with which they are respectively associated.

In any system comprising a master timer such as the timer T, or one or more local traffic signal controllers such as the controller comprising the timer mechanism CD and signal circuit controlling mechanism SC of Fig. 3, the operating characteristics of such local controllers may be further governed from the master timer.

For example, if it is desired to suspend the normal cyclic operation of the local controllers, so that the "stop" and "go" signals for the respective highways (as well as the pedestrian periods) will be discontinued, and a flashing amber warning signal substituted therefor, as is frequently desired for periods when traffic density is light (say between midnight and dawn)—the switch 242 at the master timer T may be closed, thereby establishing a current path from supply source conductor 250, through conductor 252, winding of relay N, conductor 264 (including switch 242) and conductor 258 (including switch 253) to supply source conductor 256.

The establishment of the current path just described will result in movement of contact 113 into engagement with contacts 111 and 112, of contact 115 into engagement with contact 114, and contact 117 away from contact 116.

Such separation of contact 117 from contact 75

116 causes interruption of the energizing current path hereinbefore described for solenoid E; as a result of which, rock shaft 176 will be rotated by spring 170' so as to lift projections 80' of cam 5 followers 80 associated with, and to thereby support, contact fingers 201', 202', 203', 204', 205', 206', 207', 208', 209', 209'', 210', 211', 211'', 212', 213' and 214' away from the contact strips 76, 76' and 76'' with which they might otherwise 10 co-operate; thus suspending responsiveness of all of said contact fingers to the rotation of their respectively associated cams, and preventing establishment, through any of said contact fingers, of current paths for the lighting of the signal lamps 15 at intersection S; also preventing closure of the lock-up path for relay P, and preventing closure of the energizing path for solenoid J, all of which paths have been hereinbefore more fully described.

20 The movement of contact 115 into engagement with contact 114, incidental to such energization of relay N, establishes (independently of the operation of timer mechanism CD) a current path for continuously driving motor M3 from supply 25 source conductor 300, through conductor 304, switch 306, motor M3, resistance 282, conductors 280 and 284, contacts 114 and 115, and conductor 322 to supply source conductor 302.

Engagement of contacts 111 and 112 by contact 30 113, incidental to energization of relay N, establishes current paths for the intermittent lighting of amber lamps A, A, A, A for the arterial and intersecting highways at S, subject to control by contact fingers 217' and/or 218' (as determined 35 by positioning of switch 294) through current paths from supply source conductor 302, through contact strip 76, conductor 288, contact strip 76', conductor 286, contact strip 76'', through contact finger 217' upon each engagement thereof 40 with said contact strip, if switch 294 is closed, otherwise, through contact finger 218', during each closure thereof, thence through conductor 290, to contact 113, from which parallel paths proceed, one through contact 111, conductors 45 338 and 334 to one of the terminals of each of the amber lamps A, A for the arterial highway, and the other of which paths extends through contact 112 and conductor 344 to one terminal of each of the amber lamps A, A for the intersecting highway; the remaining terminals of 50 said lamps A, A, A, A being connected to supply source conductor 300.

From the foregoing, it will be apparent that, so long as the setting is in accordance with the 55 description just given, if the switch 294 stands open, all of the amber lamps A, A, A, A of the signals at the intersection S, will flash each time one of the depressed portions of the cam 218 is presented to its associated follower 80'. On the other hand, if the switch 294 is closed, such lamps 60 will flash whenever a depressed portion of the cam 217 permits contact finger 217' to move into connection with contact strip 76'''.

As shown, cam 217 has formed therein twice 65 as many depressed surfaces as cam 218, and the setting is such that every other one of the depressed surfaces of cam 217 permits movement of contact finger 217' to closed circuit position at a time when some one of the depressed surfaces 70 of cam 218 permits contact finger 218' to move into closed circuit position. Hence, during operation under conditions now under consideration, if switch 294 is closed, the flashes of the amber lamps at intersection S will be twice 75 as frequent as when such switch stands open.

If it is desired to completely suspend response of the local traffic signal controller or controllers associated with a master timer, such as timer T, the switch 253 thereat should be opened, thus interrupting the previously established current 5 paths therethrough which have been hereinbefore more fully described, with resultant de-energization of relay N or solenoid E (whichever one had been energized up to that time) so that the rock shaft 176 would thereafter be so positioned 10 as to prevent closure of current paths for lighting any of the signal lamps at intersection S, resultant from positionings of the cams carried by the shaft 104, or resultant from closed circuit positioning of contact finger 217' or 218', and, 15 resultant cutting off of the current supply for the motor or motors M2 of the timer mechanism CD of the associated local traffic signal controller or controllers, will cause such motors to come to rest. Referring now to Fig. 3, it will be apparent 20 that if the motor M2 is brought to rest at a time when the shaft 119 is so positioned that the pin 153' is not engaging the arm 155, and the pins 151' and 152' are not engaging the dog 154, the current supply for motor M3 will thereafter be 25 cut off upon the next occasion when contact finger 225' is moved away from contact strip 76''' by any one of the raised portions of cam 225; unless, upon such occasion, the notch of cam 224 is so positioned as to permit contact finger 224' to 30 connect with contact strip 76'''.

Furthermore, even should shaft 119 stop in a position such that contacts 67 are then closed by pin 153' or contact arm 157 is being held in engagement with contact 65 or 66 by the pin 35 151' or 152', as the case might be, such fact will not cause rotation of shafts 102 and 104, beyond what would have occurred in the absence of such a contact closure, more than to the extent of the angular distance between raised portions of cam 225.

From the foregoing it will be seen that, opening of switch 253 will result in bringing motors M2 and M3 to rest and in extinguishment of 45 all of the signal lamps at S.

Thereafter, closure of switch 253 will cause 50 restoration of all activities which were interrupted by the opening of this switch, so that such activities will proceed as hereinbefore more fully described.

In situations where a "go" signal should be given to an arterial highway at all times except following the approach of traffic on an intersecting highway, signal circuit controlling mechanism corresponding to the contacts 236 of master timer 55 T may be arranged for actuation on approach of traffic on the intersecting highway in any well-known manner, whereupon operation of the remainder of the system will proceed as hereinbefore more fully described.

If, on the other hand, equipment is desired for 60 but a single intersection, the master timer mechanism T of Fig. 3 may be omitted; conductors 266 and 268 being, in that event, interconnected at any convenient point; and the local traffic controller timer mechanism CD will thereupon run continuously and suitably control the signal circuit controlling mechanism SC.

With such an arrangement, it is obvious that 65 the adjustments hereinbefore described through 70 utilization of resistance 238 would no longer be effective; however, adjustment of a resistance corresponding to resistance 240 of Fig. 3, would result in shortening or lengthening the operating cycle of shaft 119, and changes in the relative 75

durations of the respective periods could then be effected by adjustment of the arms 151, 152 and 153.

Where a plurality of local traffic controllers are associated with a master timer for the purpose of providing for so-called "progressive" or "ripple" traffic movement,—such, for example, as indicated by Figs. 9 and 12,—insofar as the needed differences in the settings of various local controllers was found to be represented by other than the time required for a complete cycle of the master timer, such diverse adjustments can be obtained by making the needful settings of the arms 151, 152 and 153 in the various local controllers.

In this connection, it will be noted in a system having local controllers whose arms 151, 152 and 153 are diversely set, it may be rendered impracticable to correspondingly revise the relative durations of the cycle components of all such local controllers by merely altering the adjustments of resistances 238 and 240 at the master controller in the manner hereinbefore referred to.

Should it be desired to manually direct traffic at an intersection having signals normally responsive to a local controller such as that of Fig. 3, such result can be accomplished by manually rotating the cam assembly on shaft 104 in the usual direction, in any desired manner. Rotation of said assembly in advance of the driving of the motor being permitted by the ratchet wheel 40 and dog 42 shown in Fig. 2.

In order that the motor shall not act through such ratchet mechanism to cause movement of the cams in advance of the desire of the operator, the switch 306 of Fig. 3 may be opened for the purpose of suspending the operation of motor M3.

After any such manual actuation of the cam assembly of shaft 104, the signals thereby controlled may be again brought in step with the master timer T by closing the switch 306, whereupon, operation of motor M3 will proceed until an impulse from the timer mechanism CD is required for its further actuation, whereupon motor M3 will stop and await the occurrence of the required impulse, and thereafter will operate in the intended relationship to the cycle established by the master timer T.

It will be noted that pursuant to the description thus far given, the starting impulses formulated by the timer mechanism CD occur but three times in each cycle. If, however, because of the traffic situation to be served at any intersection, it becomes desirable to provide four starting points in each cycle, this can be accomplished through the utilization of arm 149, and the provision of a pin therein similar to either the pin 151', 152' or 153', and a revision of the connection to contact finger 224', consisting of withdrawal of said connection from conductor 280 and its application to the conductor associated with such contact as should have a current path closed thereby responsive to such pin as might be so provided in arm 149. Thus, for example, if the pin carried by arm 149 corresponds with pin 152' carried by the arm 152, contact finger 224' should be connected to conductor 274 instead of conductor 280.

The construction and manner of securing the cams in the assembly carried by shaft 104 is such that, as will be presently more fully explained, their effective periphery outline may be conveniently revised and/or angularly displaced, should any such changes be found to be desirable for the purpose of effecting alteration in the dura-

tion of any signal aspect or component thereof, or otherwise.

Fig. 5 indicates the manner in which cams 201, 202 and 214 are mounted in their assembly group, as being representative of the construction and manner of assembly and mounting of all of the cams comprised by the assemblies associated with the shafts 102 and 104.

These cams are assembled on the sleeve 364, between the spacer rings 362, and each of said cams consists of two relatively movable discs or sections so as to be capable of presenting a greater or less angular raised portion depending upon whether the raised portions thereof are in side-by-side or overlapping relationship.

A flanged bushing 366 is secured in one end of the sleeve 364 by means of the pin 368, and another bushing 370 is secured to the other end of the sleeve 364 by means of the pin 372. Said pins 368 and 372 being situated in alignment and extending into the opening through said sleeve so as to engage the slot 374 provided in shaft 104, and thereby enable said shaft to drive said sleeve and the cam assembly secured thereto.

The end of the sleeve 364 which is associated with the bushing 370 has an external thread 376 formed thereon, same being engaged by the nut 378 which clamps the various cams and spacer rings against the flange of bushing 366 in desired positions upon said sleeve.

Each of the spacer rings 362 carries an inwardly projecting pin 380 (see Fig. 6) for engaging an axial slot 382 formed in the sleeve 364.

When it is desired to vary the configuration of any of the cams of this assembly, the nut 378 is first loosened, and then the sections of the desired cam or cams are relatively moved so as to provide the desired configuration, and the nut 378 is thereupon again tightened so as to retain the various parts as set.

Each of the spacer rings 362 has formed in the periphery thereof a series of setting lines 384, as shown in Figs. 2, 5 and 6; said lines being arranged on each spacer in four groups, with an extra large space between the last line of one group and the first line of the next group. The positionings of these lines materially facilitate attainment of desired settings of cam configurations, as will be well understood by those skilled in this art.

As an example of the facility with which the system and equipment hereinbefore described may be adapted for utilization in connection with traffic signals at intersections having widely diverse characteristics, reference is made to Fig. 10, which indicates an intersection comprising a main or arterial highway 450, a principal intersecting highway 452, 452 and a minor intersecting highway 454. It is assumed that the traffic conditions are such as render it desirable that, in the absence of traffic approaching along the minor intersecting highway 454, each cycle of the traffic signal controlling mechanism should alternately provide "go" and "stop" signals for the main highway 450 and the principal intersecting highway 452, 452; but that, when traffic has approached the intersection along the minor intersecting highway 454, it is desired that "stop" signals shall be given for highways 450 and 452 and that a "go" signal shall be given for highway 454, the duration of the "go" signals for highways 450 and 452 being shortened for the then current cycle to an extent sufficient to provide needed time for movement of traffic from highway 454 into or across the intersection.

For meeting these conditions, signal lamp groups 456, 456 are provided for the principal intersecting highway and 458, 458 are provided for the arterial highway, and a corresponding group 5 460 is provided for the minor intersecting highway; the connections between such signal lamps and the contact fingers indicated in Fig. 3 being similar to those there shown, except that the right-turn arrow lamps 48 and 50 are not provided and the contact fingers otherwise used for the control of such lamps and for the control of other lamps incidental to "pedestrian periods" are utilized for controlling the lamps in the group 10 460. A pad or roadway contact device 462 is provided in the minor intersecting highway 464 for actuation by traffic moving in said highway toward the intersection.

The characteristics of the operating cycles and their various component parts, for an intersection such as that indicated in Fig. 10, are graphically indicated by the chart of Fig. 11 which, considered in the light of the explanation of the chart of Fig. 7 is believed to be self-explanatory.

It is believed that the explanations hereinbefore given as to illustrative applications of this invention to certain of the many possible uses thereof, when considered in connection with the accompanying drawings, will enable those skilled in this art to readily apply this invention in all situations to which it is suited.

Claim is made to and it is desired to secure by Letters Patent of the United States of America, all generic and specific features of the invention shown by the accompanying drawings and hereinbefore more fully described, including all features which may, as a matter of language, be said to fall between the scope of any of the following claims.

We claim:

1. In a traffic control system, signals for governing traffic movements, means for effecting displays of said signals in accordance with one or another of a plurality of types of cycles which differ in number of component periods, a pedestrian responsive device, a lock-up pedestrian memory relay associated with said device for initial energization responsive to actuation thereof, means responsive to energization of said relay only at a predetermined stage of a cycle for effecting substitution of one for another of such types of cycles whereby actuation of said second named means will be held in abeyance until such predetermined period, means responsive to said second named means for effecting deenergization of said relay, and means periodically effective for restoring said second named means to its initial condition.

2. In a traffic control system, signals for governing traffic movements, means for effecting displays of said signals in accordance with one or another of a plurality of types of cycles which differ in number of component periods, a pedestrian responsive device, a lock-up pedestrian memory relay associated with said device for initial energization responsive to actuation thereof, means responsive to energization of said relay only at a predetermined stage of a cycle for effecting substitution of one for another of such types of cycles whereby actuation of said second named means will be held in abeyance until such predetermined period, and means periodically effective for restoring said second named means to its initial condition.

3. In a traffic control system, signals for governing traffic movements, means for effecting dis-

plays of said signals in accordance with one or another of a plurality of types of cycles which differ in number of component periods, a pedestrian responsive device, a lock-up pedestrian memory relay associated with said device for initial energization responsive to actuation thereof, and means periodically operable responsive to such energization for governing the alternative effectiveness of such types of cycles.

4. In a traffic control system, traffic signalling means located at an intersection having two or more intersecting traffic lanes, a rotary switching mechanism for controlling the display of said signals in accordance with one or another of a plurality of types of signal cycles which differ in number of component periods, a timing means for controlling the time of initiation and duration of periods of said cycles, a selector means for causing one of said types of cycles to be normally displayed by said switching mechanism, a lock-in relay, a switch operable to actuate the lock-in relay, means responsive to the said lock-in relay for operating said selector means and operable in a predetermined relationship to the position of said switching mechanism to cause the selector means to substitute the other said type of signal cycle, and means for restoring the selector means to its normal position to cause the first said type of signal cycle to be again displayed.

5. In a traffic control system, traffic signalling means located at an intersection having two or more intersecting traffic lanes, a rotary switching mechanism for controlling the display of said signals in accordance with one or another of a plurality of types of signal cycles which differ in number of component periods, a timing means for controlling the time of initiation and duration of periods in said cycles, a selector means for causing one of said types of cycles to be normally displayed by said switching mechanism, a lock-in relay, a switch operable to actuate the lock-in relay, means responsive to the said lock-in relay for operating said selector means and operable in a predetermined relationship to the position of said switching mechanism to cause the selector mechanism to substitute the other said type of signal cycle, and means for restoring the selector means to its normal position to cause the first said type of signal cycle to be again displayed at a predetermined point in the cycle.

6. In a traffic control system, signal indicating means located at a series of intersecting traffic lanes, a master timing means, a series of secondary timers located at the signalized intersections, synchronizing means for synchronizing the secondary timers with said master timer, a switching mechanism operatively responsive to said timing means for changing the signal indications of the signal indicating means at preset intervals in accordance with one or another of a plurality of types of cycles which differ in number of component periods, a control switch associated with the individual switch mechanism, an electromagnetic selector means responsive to actuation of said control switch for selecting one of the plurality of said cycles to be displayed, said selector means being arranged to permit one type of cycle to be normally displayed and to substitute a second type of cycle in response to actuation of said control switch, and means for delaying the responsiveness of the selector means to the actuation of said switch to occur only during a predetermined period which may be preselected

as the one least impeding the progressive movement of traffic along the highway.

7. A traffic control system to be applied at a plurality of traffic lane intersections at least one of which has three intersecting traffic lanes and comprising signalling means to accord and to interrupt the right-of-way over said lanes and to be located adjacent each intersection, operating means for said signalling means to cause the display of signal indications in accordance with one or another of a plurality of types of cycles differing in number of component periods, means for normally causing the display of one of said types of cycles to accord and to interrupt the right-of-way over two of the intersecting lanes of the intersection having three intersecting lanes without according the right-of-way to a third lane, a device actuated by traffic approaching the intersection in the said third lane, connections between the said device and the last mentioned means to cause said means to substitute upon actuation of said device the display of a second type of cycle for the first type whereby a right-of-way signal indication is accorded the third lane, and means for delaying the responsiveness of the last mentioned means to said device until a predetermined signal indication is displayed which may be preselected as the one during which the substitution of types of cycles will least impede a progressing movement of traffic along the main traffic lane.

8. A traffic control system to be applied at an intersection of a plurality of intersecting traffic lanes and comprising signalling means to accord and to interrupt the right-of-way over said lanes, operating means for said signalling means to cause the display of signal indications in accordance with one or another of a plurality of types of cycles differing in number of component periods, means for normally causing the display of one of said types of cycles to accord and to interrupt the right-of-way over two of the intersecting lanes without according the right-of-way to a third lane, a device actuated by traffic approaching the intersection in a third lane, connections between the said device and the last mentioned means to cause said means to substitute, upon actuation of said device, the display of a second type of cycle for the first type whereby a right-of-way signal indication is accorded the third lane, and means for delaying the responsiveness of the said last mentioned means to said device until a predetermined signal indication is displayed.

9. In a traffic control system, the combination comprising a plurality of circuits each adapted to energize a traffic control signal, means for energizing said circuits cyclically, and means to change the cycle of energizing said circuits to a cyclic energization varying from the first mentioned cycle with respect to the number of component periods thereof.

10. In a traffic control system, the combination comprising a plurality of circuits each adapted to energize a traffic control signal, means for energizing said circuits cyclically, an actuating circuit including traffic responsive means, and means responsive to traffic operation of said actuating circuit to change the cycle of energizing said circuits to a cyclic energization varying from the first mentioned cycle with respect to the number of component periods thereof.

11. In a traffic control system, the combination comprising a plurality of circuits each adapted to energize a traffic control signal, switches

for controlling said circuits, cyclic means for actuating said switches cyclically, and controlling means to vary the grouping of switches responsive to actuation by said cyclic means whereby, in various positions of adjustment of said controlling means, said switches actuate said circuits in cycles differing in number of component signal periods of each cycle, all of said cyclic means being coordinately actuated whereby, whenever said controlling means is shifted from one position to the other, any particular point in either cycle will always shift to a co-ordinated particular point in the other cycle.

12. In a traffic control system, the combination comprising a plurality of circuits each adapted to energize a traffic control signal, switches for controlling said circuits, cyclic means for actuating said switches cyclically, controlling means to vary the grouping of switches responsive to actuation by said cyclic means whereby, in various positions of adjustment of said controlling means, said switches actuate said circuits in cycles differing in number of component signal periods of each cycle, all of said cyclic means being coordinately actuated whereby, whenever said controlling means is shifted from one position to the other, any particular point in either cycle will always shift to a coordinated particular point in the other cycle, a circuit comprising a lock-in memory relay operated switch and an actuating switch, cyclic means coordinately actuated with the first mentioned cyclic means whereby said actuating switch is actuated at a particular coordinated point in said cycles, and means responsive to actuation of said actuating switch following actuation of said relay to shift said controlling means.

13. In a traffic control system, the combination comprising a plurality of circuits each adapted to energize a traffic control signal, means for energizing said circuits cyclically, and a circuit including traffic responsive means and electrical means responsive to said traffic responsive means to change the cycle of energizing said circuits at the next occurrence of a predetermined time in said cycle to a cyclic energization varying from the first mentioned cycle with respect to the number of component periods thereof.

14. In a traffic control system, signals for governing traffic movements at respective ones of a plurality of highway intersections, a series of controlling means each comprising mechanism associated with and operable for effecting displays of said signals at respective ones of said intersections in accordance with one or another of a plurality of types of cycles which differ in number of component periods together with initiating means for effecting timely initiation of the operative cycle thereof, a master controlling equipment comprising means for governing the initiating means for said intersections, a plurality of traffic responsive devices, lock-up relays associated with said devices and with the controlling means associated with said intersections for initial energization upon actuation of said devices, means associated with each of said controlling means for effecting substitution of one for another of such types of cycle displays and responsive to energization of respective ones of said relays for operation only during a predetermined period of a cycle whereby actuation of one or more of said devices will be held in memory until such predetermined period, means associated with said controlling means for effecting deenergization of said relays upon operation of

their respectively associated ultimately responsive means, and means periodically effective for restoring said responsive means to their initial conditions whereby progressive signaling and movement of traffic may be permitted and the effectiveness of such substituted types of cycles will occur only during a predetermined period of a cycle which period may be preselected as the one least impeding such progressive traffic movement.

15. In a traffic control system, signals for governing traffic movements at respective ones of a plurality of highway intersections, a series of controlling means each comprising mechanism associated with and operable for effecting displays of said signals at respective ones of said intersections in accordance with one or another of a plurality of types of cycles which differ in number of component periods together with initiating means for effecting timely initiation of the operative cycle thereof, a master controlling equipment comprising means for governing the initiating means for said intersections, a plurality of traffic responsive devices, lock-up relays associated with said devices and with the controlling means for initial energization upon actuation of said devices, and means associated with each of said controlling means for effecting substitution of one for another of such types of cycle displays

and responsive to energization of respective ones of said relays for operation only during a predetermined period of a cycle whereby progressive signaling and movement of traffic may be permitted and the effectiveness of such substituted types of cycles will occur only during a predetermined period of a cycle which period may be preselected as the one least impeding such progressive traffic movement.

16. In a traffic control system, traffic signalling means located at an intersection having two or more intersecting traffic lanes, a rotary switching mechanism for controlling the display of said signals in accordance with one or another of a plurality of types of signal cycles which differ in number of component periods, a timing means for controlling the time of initiation and duration of periods in said cycles, a selector means for causing one of said types of cycles to be normally displayed by said switching mechanism, a lock-in relay, a switch operable to actuate the lock-in relay, and means responsive to the said lock-in relay for operating said selector means and operable in a predetermined relationship to the position of said switching mechanism to cause the selector mechanism to substitute the other said type of signal cycle.
